Primary Examiner — Raphael Barkai

(74) Attorney, Agent, or Firm — Wood, Herron & Evans,
LLP(57) **CLAIM**

The ornamental design for glasses for watching 3D image, as shown and described.

DESCRIPTION

FIG. 1 is a top front perspective view of glasses for watching 3D image showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict environmental subject matter only and form no part of the claimed design.
